US00D605180S

(12) **United States Design Patent**
Rudolph et al.

(10) **Patent No.:** **US D605,180 S**
(45) **Date of Patent:** **** Dec. 1, 2009**

(54) **ENTERTAINMENT DEVICE REMOTE
CONTROL**

(75) Inventors: **Daniel L. Rudolph**, Castle Rock, CO (US); **Luke VanDy whole**, Highlands Ranch, CO (US)

(73) Assignee: **EchoStar Technologies, L.L.C.**, Englewood, CO (US)

(**) Term: **14 Years**

(21) Appl. No.: **29/338,203**

(22) Filed: **Jun. 5, 2009**

(51) **LOC (9) Cl.** **14-03**

(52) **U.S. Cl.** **D14/218**

(58) **Field of Classification Search** **D14/218, D14/455, 341, 345, 346; D13/168; D21/566; D10/104, 106; 345/169; 348/14.05, 114, 348/211.99, 734; 340/825.24, 825.69; 341/22; 455/92, 95, 128, 151.1-151.4, 352, 355, 455/FOR. 121; 700/65**

(57) **CLAIM**

The ornamental design for an entertainment device remote control, as shown and described.

DESCRIPTION

FIG. 1 is a top view of the entertainment device remote control showing our new design;

FIG. 2 is a bottom view thereof;

FIG. 3 is a left side view thereof;

FIG. 4 is a right side view thereof;

FIG. 5 is a top perspective view thereof; and,

FIG. 6 is a bottom perspective view thereof.

In the drawings, the broken-line showing of buttons depicts environmental subject matter only and forms no part of the claimed design.
